UNITED STATES PATENT OFFICE.

ADELMER M. BATES, OF CLEVELAND, OHIO, ASSIGNOR TO BATES VALVE BAG COMPANY, OF CLEVELAND, OHIO, A CORPORATION OF WEST VIRGINIA.

BAG-CRIMPING DEVICE.

No. 918,495.

Specification of Letters Patent.

Patented April 20, 1909.

Application filed January 10, 1906. Serial No. 295,368.

To all whom it may concern:

Be it known that I, ADELMER M. BATES, a citizen of the United States, residing at Cleveland, in the county of Cuyahoga and State of Ohio, have invented a certain new and useful Improvement in Bag-Crimping Devices, of which the following is a specification.

My invention relates to means for holding, crimping and tying the open ends of bags. It is intended particularly for use in connection with valve bags.

The drawing is to be taken as in most particulars diagrammatic and illustrative simply of a rude form of device which can be easily varied at will to carry out the idea.

Where the bag is the measure or where a set of bags are filled with a uniform amount of material, that amount depending on the capacity of the bag, it is obviously necessary to have a uniform method of tying so as to secure, with a given set of bags of a certain size, uniformity of capacity.

In the case of valve bags where the bag is filled at one end through a valve opening and is opened and its contents discharged at the other end, it is plainly important that the empty bag should be retied in a uniform manner so that all bags of a given size when filled through the valve shall have the same contents.

Referring to the drawings, Figure 1 is a plan view of a number of holding devices; Fig. 2 is an end view of one such holding device, Fig. 3 is a side view of a holding device with the bag extended, Fig. 4 is a similar view with the bag crimped and tied. Fig. 5 is a plan view of the crimping end of the bag.

Like parts are indicated by the same letter in all the figures.

A is a cross piece suitably supported by brackets B against the wall or vertical standard C. At intervals along its top the cross piece A is slotted and there is let into it the two parts D D of a spring holding device. These parts are extended as indicated and are rounded at their outer ends at D¹ to form a receiving mouth for the bags. These

pieces D D are preferably of spring or elastic wood and they tend to force themselves tightly together. To facilitate this action, they may be cut out at E and be adjustably

clamped together by the bolt F and thumb-nut F¹. G is a stop pin, H H stop pegs, one of them with a cutting edge, J a stop plate and K a flattened spiral spring surrounding the two pieces D D and bearing at one end against the stop pin G and at the other against the stop plate J. L is a bag having at one corner an inwardly opening valve L¹ and adapted to be crimped at the top, as indicated at L². M is the twine with which the bag is tied and it is drawn from the reel M¹ mounted on the stop plate J. As illustrated, one of the pins H has a cutting edge at H¹. As previously mentioned these parts are in an important sense diagrammatic and some may be dispensed with without affecting the action of the others.

The use and operation of my invention are as follows: Assuming a series of spring holders like those illustrated in Fig. 1, each with its several parts and its separate reel and ball of twine, the operator will take up an empty bag and by pulling it forward by the edge O force it against the action of the spring forward between the two spring pieces D D, and this will bring it into the position indicated in Fig. 3. If now he draws it backward toward himself in the direction indicated by the arrow in Fig. 3, or if, having the spiral spring in place, he releases the bag and allows the spring to operate, the result would be that the bag is folded or crimped at its top in a highly uniform manner, the crimped portion being gathered in the recess end formed by the two opposed slots near the ends of the parts D D. The cord is placed with the edge of the bag and stop H H on one side and the plate J on the other so when the bag comes back into the position for tying, the twine will be in position. It can now be tied as indicated in Fig. 4, either by the first or another operator, and can then be jerked out of the holder.

As indicated in Fig. 5, the crimps L² are uniform and an arrangement which will bring about this result is, of course, preferable. The tying of the bag can be accomplished by hand or by machinery in any desired manner.

Where the bag is stretched out in the manner indicated, it can be crimped with great ease and regularity and at a uniform

distance from the edge so as to insure a practically uniform capacity for each of the series of bags.

I claim:

5. 1. A bag crimping device comprising clamping members secured at one end and separable at the other to admit the bag, one of said members being recessed at the separable end so as to form near one end of the said members a crimping holding portion, and a support to which the clamping members are secured.
10. 2. A bag crimping device comprising clamping members secured at one end and separable at the other to admit the bag, one of said members being recessed so as to form near one end of the said members a crimping holding portion and means connected with said members for forcing a bag held between them into said crimping holding portion, and a support to which the clamping members are secured.
15. 3. A bag crimping device comprising clamping members secured at one end and separable at the other to admit the bag, one of said members being recessed so as to form near one end of the said members a crimping holding portion, and means connected with said members for forcing a bag held

between them into said crimping holding portion, said means comprising a spiral spring surrounding the members and abutting a fixed bearing at the end away from the holding portion, and a support to which the clamping members are secured.

30. 4. A bag crimping device comprising two clamping members secured to a support at one end, means for holding said members in elastic contact with each other throughout the greater part of their lengths, both of said members being recessed near their outer ends so as to form a crimping holding portion.

35. 5. A bag crimping device comprising two clamping members secured to a support at one end, means for holding said members in elastic contact with each other throughout the greater part of their lengths, both of said members being recessed near their outer ends so as to form a crimping holding portion, and means connected with said members for forcing a bag held between them into said holding portion.

ADELMER M. BATES.
